UNITED STATES PATENT OFFICE

JACOB WOLF, OF MILWAUKEE, WISCONSIN, ASSIGNOR OF ONE-HALF TO ISADORE SAX
AND MARCUS SAX, COPARTNERS DOING BUSINESS AS SAX BROS.

HEEL ATTACHING DEVICE

Application filed December 11, 1930. Serial No. 501,522.

The invention relates to a shoe heel attaching device.

The object of the invention is to provide a shoe heel attaching device consisting of few parts that may readily and economically be produced and that will efficiently perform the function of holding the heel in position against the heel seat of the shoe while attaching said heel thereto.

10 A further object of the invention is to provide a heel attaching device wherein the clamping member is adjustably mounted at one end of a lever which is pivotally mounted on a support that has a heel receiving 60 pocket associated therewith, the other end of said lever being associated with a jack screw which also cooperates with the support and acts to move said lever and clamping member to its clamping position and maintains 65 it in this position while driving in the nails or other attaching devices securing the heel to the shoe.

The invention further consists in the several features hereinafter set forth and more 25 particularly defined by claims at the conclusion hereof.

In the drawings, Fig. 1 is a side elevation, 30 view of the device embodying the invention, parts being broken away and parts being shown in section;

Fig. 2 is a detail sectional view taken on the line 2—2 of Fig. 1;

Fig. 3 is a detail sectional view taken on the line 3—3 of Fig. 1.

35 Referring to the drawings, the numeral 6 designates a support preferably formed as a one piece casting having shoe heel receiving recess or seat 7, a socket portion 8, an inclined side socket or recess 9, an upstanding arm 10 having a forked upper end 11, and a hand hold opening 12.

The socket portion 8 is adapted to detachably receive the upper end of a cobbler's last-holding standard 13.

40 The tapered and curved side of the heel receiving recess is preferably lined with cushioning material 14 such as felt.

45 A lever 14 is pivotally mounted intermediate its end on a pivot bolt 15 adapted to be inserted in one of a series of vertically spaced

holes 16 in the forked upper end 11 of the support 6. This lever has a handle 17 at one end and a slot 18 at this end adjacent the handle.

A clamping member 19 has a shoe engaging head 20 and a shank 21 whose upper end projects through the outer end of the slot 18 and is pivotally connected to the lever 14 at this point by a pivot pin 22.

55 A screw or jack shaft 23 has its forked upper end 24 pivotally connected by a pin 25 with the opposite end of the lever 14 from that carrying the member 19 and its free end projects into the socket 9 in the support 6.

60 A manually operable or turnable nut 26 is mounted on the screw shaft 23 and is adapted to abut against the support 6 adjacent the recess 9.

65 The head 20 is provided with spaced nail passages 27 and a nail set or driver 28 has its 70 lower end of reduced section to work in said passages. With the above construction, a

75 heel 29 to be attached to the shoe 30 is placed in position in the recess 7 and the heel seat of the shoe portion over the same generally with adhesive applied between these two parts, and then the operator grasping the 80 handle 17 of the lever, brings the clamping member down against the heel seat portion of the shoe and holds it there while turning

85 the nut 26 down on the screw shaft 23 until said nut engages the support with sufficient pressure to hold the parts in this position.

Then the nails such as 31 may be inserted in the holes or passages 27 and driven into the 90 heel seat of the shoe and the heel to fasten the heel in position, it being noted that the slot 18 in the lever permits the driver 28 to be inserted therethrough to take care of the nail at the rear of the heel and that this driver is disposed at the sides of the lever and does not interfere with the same in taking care of the attachment of the other nails or fastening devices.

95 The device is shown is adapted to take care of the ordinary high heels, though by lowering of the pivot bolt 15 into the lower hole 16, lower heels may be accommodated.

100 The device is simple in construction, requires very little machine work for its man-

ufacture, is easy to operate and insures an accurate alinement between the heel and shoe while securing these parts together.

I desire it to be understood that this invention is not to be limited to any particular form or arrangement of parts except in so far as such limitations are included in the claims.

What I claim as my invention is:

1. In a device of the character described, the combination of a support having a heel receiving portion, an arm projecting above said portion, said support having a recess adjacent said arm, a lever pivotally mounted on said arm, a clamping member pivotally mounted on one end of said lever and adapted to engage the shoe to clamp the same against the heel while attaching the heel, a screw shaft operatively connected with the other end of said lever and having its free end working in said recess, and a nut on said screw shaft cooperating with said support to move said shaft and lever to bring and maintain said clamping member in a clamped position.

2. In a device of the character described, the combination of a support having a heel receiving portion, an arm projecting above said portion, said support having a recess adjacent said arm, a lever pivotally mounted on said arm and having a handle, a clamping member pivotally mounted on said lever adjacent said handle and adapted to engage the shoe to clamp the same against the heel while attaching the heel, a screw shaft operatively connected with the opposite end of said lever and having its free end working in said recess, and a nut on said screw shaft cooperating with said support to move said shaft and lever to bring and maintain said clamping member in a clamped position.

3. In a device of the character described, the combination of a support having a heel receiving portion, an arm projecting above said portion, said support having a recess adjacent said arm, a lever pivotally mounted on said arm, a clamping member pivotally mounted on one end of said lever and engageable with the shoe to clamp the same against the heel while attaching the heel, said member having openings therein for the passage of fastening means, said lever being slotted adjacent said clamping means to admit of the insertion of a driver therethrough for said fastening means, a screw shaft pivotally connected with the other end of said lever and having its free end working in said recess, and a nut on said screw shaft cooperating with said support to move said shaft and lever to bring and maintain said clamping member in a clamped position.

4. In a device of the character described, the combination of a support having a heel receiving portion and an upstanding arm, a lever pivotally mounted intermediate its ends on said arm and having a handle at one end,

a clamping member pivotally mounted on said lever adjacent said handle and engageable with the shoe to clamp the same against the heel, and lifting means between the other end of said lever and said support to raise this end of said lever and exert a clamping pressure through said lever on said clamping member.

5. In a device of the character described, the combination of a support having a heel receiving portion and an upstanding arm, a lever pivotally mounted intermediate its ends on said arm, a clamping member operatively connected to one end of said lever and engageable with the shoe to clamp the same adjacent the heel while attaching the heel, and lifting means between the other end of the lever and said support to raise this end of said lever and exert a clamping pressure through said lever on said clamping member.

In testimony whereof, I affix my signature.

JACOB WOLF.
